METHOD AND APPARATUS FOR EMBALMING

Ray Emerson Slocum, Oakland, Calif., and Fuller E. Blickens, Carbondale, Pa., assignors to The Dodge Chemical Company, Boston, Mass., a corporation of Massachusetts

Application January 27, 1949, Serial No. 73,134

22 Claims. (Cl. 27—21)

1

This invention relates to the art of embalming and more especially to methods and apparatus for maintaining and/or restoring the appearance of a cadaver to as near lifelike proportions and contours as possible.

One of the more difficult problems confronting the embalmer in preparing a cadaver for final appearance is to give the exposed areas, primarily the face and the neck, lifelike qualities either by preserving the appearance of a body which has not suffered material changes prior to death or to restore the features of bodies which have undergone distortion, emaciation or swelling prior to death to as near the original normal condition as possible. This has been done heretofore largely by molding the features prior to, during and after the injection of the preservative fluid with the finger tips and with the aid of wads of cotton and/or other wadding, such as plastic material judiciously placed within the mouth to hold the lips, checks, jowls and other soft parts of the face properly contoured. This, however, requires a considerable amount of skill which is acquired only after long experience and in many cases is never mastered, so that the results are frequently unsatisfactory and cause undue added distress to those most concerned.

Objects of this invention are primarily to minimize the tendency of certain types of bodies to become swollen during the arterial injection of the preservative fluid, due in part to senile changes that make the superficial tissues less resistant to the entrance of the embalming fluid than are the deep tissues, and in part to injection of the arterial solution faster than the tissue can assimilate it, or by the use of an excessive amount of solution injected into the facial areas in an attempt to force some solution into areas that do not so readily receive the solution so that a superfluous amount of the solution following the course of least resistance reaches the superficial tissues and produces swelling of the face and neck.

Another object of the invention is to prevent unanticipated excessive flooding of the superficial tissues during arterial injection and to provide means for immediately controlling such excessive flooding, should it occur in these areas, as soon as they show any signs of distention.

Another object of the invention is to reduce distention of the temples, eyes, cheeks or jowls, lips or chin and the thyroid areas of the neck caused by the presence of dropsical fluids so that when the embalming has been completed facial distentions will have been practically eliminated.

2

Another object is to correct distention and/or unpleasant contours produced in bodies which have already been improperly embalmed by changing the contours of the temples, eyes, cheeks or jowls, lips or chin and the thyroid areas of the neck that were not treated prior to injection so as to restore them to their lifelike condition.

A further object is to reduce swelling due to traumatic injury or disease wherein no attempt was made to reduce the same during arterial injection or where the treatment has been made but was only partially successful because the extent of distortion was so great that the correct amount of pressure applied would have interfered with securing tissue penetration of the preservative.

A still further object of the invention is to shorten the time usually consumed in molding areas that have been destroyed by disease or accident and to assist in reproducing and rebuilding areas with or without use of plastics and/or other moldable materials.

A still further object of this invention is to aid student embalmers in becoming skilled in molding various portions of the face and neck to satisfactory contours by providing molds of average or overall common contour which may be used as guides.

A still further object of the invention is to provide for selectively conducting the embalming fluid in greater or lesser quantities to different parts of the body, for example, to the back of the neck in stout bodies wherein the neck is short and the jowls tend to sag so as to induce greater tissue fixation and hence to discourage undesirable tissue sagging that is so often embarrassing.

A still further object of the invention is to eliminate pouchy areas and wrinkling caused by low resistance of the tissue in these areas to the passage of the embalming fluid.

A final object of the invention is to control the amount of embalming fluid injected into the body by preventing assimilation thereof in certain areas which are more absorptive than others with accompanying overembalming.

In accordance with the foregoing objects, the invention in one aspect resides in a method of treating the cadaver by applying forming members to the affected areas which have surfaces of such shape that the converse of this surface is as nearly lifelike as possible, and securing the form in place over the area under pressure while the embalming fluid is being injected and leav-

ing the form in place until the fluid sets, whereupon it may be removed. By using the proper amount of pressure, swollen areas may be reduced and swelling of areas which have been diseased and would assimilate too much fluid will be constrained so as to prevent assimilation of excessive fluid. Areas which have become emaciated may, moreover, be rounded out or plumped to their normal contours by injection of the fluid in sufficient amounts to force the facial tissue into surface contact with the mold. In one aspect the flow of fluid may be accelerated to produce a concentration of the fluid in certain parts or areas so as to impart rigidity thereto upon setting of the fluid and hence assisting in fixing the position of the cadaver after it has been suitably arranged.

In another aspect control of the flow of embalming fluid is effected by selectively changing the capacity of the vascular system in a given part or area by dilating or constricting the same. Dilatation is accomplished by applying heat to the part to accelerate the flow, while constriction is accomplished by applying cold thereby to retard the flow to or through the area. As illustrated, the heating and cooling effects are produced by transmitting the heat or cold to the area through the forming members.

In accordance with another feature of the invention, the apparatus for shaping, molding and controlling the flow of embalming fluid into the cadaver is constituted by one or more rigid molding members, each of which has a molding surface, the converse of which corresponds closely to the normal shape of the healthy tissue. One or more of such molding members are applied to the part or area which is to be treated and held in place thereagainst during the injection of the embalming fluid and while the latter sets, whereupon they may be removed. The rigid molding members are preferably formed of a plastic material molded to shape and have bordering areas which nondefinitively merge therewith and are of opposite curvature so that no line of demarcation will appear on the surface tissue after the molding operation which might be disfiguring. In conjunction with the molds to hold them in place, there are elongate hollow binding members each of which has at its opposite ends flexible binding cords with which it may be bound around the cadaver in the proper position embracing the forming member or members. The hollow binding member is in the form of an elastic bag having collapsible walls of rubber-like material, and has a capped opening through which may be introduced a fluid to expand the bag, and, if desirable, to conduct heat or cold to the underlying forming members.

In accordance with the invention, the forming members are constituted by right and left temple forms, right and left eye forms, right and left cheek or jowl forms, right and left thyroid forms, and an upper lip and lower lip and chin form. It is to be understood, however, that forms of appropriate shape may be employed for other parts of the head and neck and, if desirable, for other parts of the body.

The invention will now be described in greater detail with reference to the accompanying drawings wherein:

Fig. 1 shows a right side elevation of the head of a cadaver with the areas which are to be treated during the injection of the preservative fluid outlined in dot and dash lines indicating

the general shape of the forming member to be applied thereto;

Fig. 2 is a cross section of the head, looking from the top, in a horizontal plane just above the eyes showing a forming member applied to each eye and binding means for holding them in place;

Fig. 3 shows the head portion of a cadaver which is in a prone position with the head resting on a support and with several forming members applied to various areas and secured in place, the binding means being shown in dot and dash lines;

Fig. 4 is a longitudinal side view of the binder member, partly in section;

Fig. 5 is a plan view of the right forming member which is to be applied to the thyroid area, there being two, one for the right side and one for the left side of the throat;

Fig. 5a is a view looking toward the left end of Fig. 5;

Fig. 5b is a section on the line 5b—5b of Fig. 5;

Fig. 6 is a longitudinal section taken on the line 6—6 of Fig. 5;

Fig. 7 is a plan view of the right cheek forming member;

Fig. 8 is an edge view of the right cheek forming member shown in Fig. 7;

Fig. 9 is a plan view of the right temple forming member;

Fig. 15 is a top view of the upper lip forming member;

Fig. 16 is an inside elevation of the upper lip forming member looking in the direction of the arrows 16—16 of Fig. 15;

Fig. 17 is a plan view of the binder member; and

Fig. 18 is a front view of the face showing the use of building material in conjunction with a cheek forming member.

In the art of embalming, one of the most annoying and difficult problems is to preserve or restore the exposed surfaces of the cadaver in or to a condition which is as near lifelike as possible. The exposed areas, however, are constituted mainly by the face and neck which have various soft portions which are unsupported by bone structure and hence are prone to change their shape following death, particularly if the deceased person underwent prolonged illness of a kind which caused extreme emaciation or of a kind which caused swelling due to the accumulation of dropsical fluids or to traumatic injuries. Such areas are illustrated in conjunction with the illustrated head H in Fig. 1 as comprising the

temple areas T at the left and right sides of the forehead, the visual areas including the eyes E and lids at the left and right side of the nose, the cheek areas C at the left and right side of the face which lie between the hinge point of the jaws below the cheek bones, the upper and lower lip areas including the chin designated as L, and the thyroid areas which extend from near the back of the neck forwardly to the front of the neck indicated at N. These areas being unsupported and being of a soft rather loose texture

are prone to become distorted for some one of the reasons assigned above, and heretofore it has been customary to restore these areas to their normal contour by judicial placing of wads of cotton or other plastic material within the mouth or under the skin and molding the parts with the fingers so as to impart as lifelike an appearance as possible. This involves considerable artistic skill and experience which is frequently never mastered and often consumes considerable time.

According to the present invention, it has been found that by following suitable steps during the embalming period, that is, during the arterial injection of the embalming fluid, and by the use of suitably applied forming members to the external surfaces of the face and neck in the vicinity of the foregoing areas, the face and neck may be preserved in their original condition if these areas have not been unduly afflicted or may be restored to nearly their normal condition free of wrinkles and other imperfections. According to the present practice, the blood and water are withdrawn from the vascular system of the body and the embalming fluid is arterially injected with sufficient pressure to insure the fluid's reaching every part of the body, and hence insuring complete preservation against decay. Since, as pointed out, there are certain areas which are soft and others that are firm, there is a considerable variation in the resistance of the tissue to take up or assimilate the embalming fluid, with the result that when sufficient pressure is employed to cause permeation of the firmer underlying parts of the body, there may be an undue or superfluous accumulation of fluid in the softer parts accompanied by distention which disfigures these parts. Furthermore, an excessive use of the embalming fluid is not desired where it is not necessary.

To overcome the disadvantages inherent in prior practice, the present invention contemplates controlling the flow of the embalming fluid into the vascular system in a manner to restrict accumulation of excessive fluids in the soft areas which readily assimilate it and to allow normal free flow through areas which are more resistant to assimilation or even to accelerate flow into resistant areas. As practiced, pressure is applied, for example, to the temple areas T on opposite sides of the head, while the embalming fluid is being injected, by means of forming members, which will be described hereinafter, and the pressure is maintained in these areas until the embalming fluid has been assimilated and sets, whereupon the forming members are removed. Pressures in the order of $\frac{1}{2}$ to 1 pound are adequate and should be maintained continuously throughout the injection period. In severe cases a pressure of 2 pounds may be applied, but when a heavier pressure is used it should be let up periodically to permit observation of the part being treated, to determine the rate of change in the area and either to permit freer flow of the fluid or a more restricted flow of fluid to the tissue. By applying the forming members under just the right pressure, a slight convexity is imparted to the surface and to the tissue immediately thereunder which is characteristic of the normal contour of the temples and which will reduce any swelling which might be present or prevent any swelling that might be produced by the injection of the embalming fluid. That is, by applying pressure to the area, the fluid ducts beneath that area are somewhat constricted so that less fluid can get to that area

while the surrounding areas are free to take up their normal quota. In like manner the cheek areas, the visual areas, the mouth area and neck or thyroid area may be treated. In addition to reducing swelling, it may be that it is necessary to build up an emaciated area, for example, in the cheeks or the neck, and when this is so the forming members applied to these parts will serve as a limiting device against which the underlying flesh may be caused to swell or plump up into contact therewith by injection of a suitable quantity of embalming fluid into that area. This is particularly true of the eyes where injection of an excessive amount of embalming fluid would cause protrusion thereof and a dearth of fluid would produce a sunken effect. By providing molding members which will limit the protrusion of the eyes, the embalming fluid may be injected under sufficient pressure to bring the eye into contact with the molding surface, and when the fluid sets the eyes will remain fixed in their normal position.

When the cadaver has been treated without the use of the foregoing method and apparatus, which will be described hereinafter, and the embalming has been completed, as, for example, by another party, swollen or distended areas may be corrected by the application of the forming members and pressures of 10 to 20 pounds for approximately one hour, the time varying, however, in accordance with the extent of distention and the fixation of the tissue in each individual case. A maximum of two hours should suffice to correct the most severe cases.

To reduce swelling due to traumatic injury or disease wherein no attempt was made to reduce the same during arterial injection or wherein treatment had been made but was only partially successful because the extent of distortion was so great that the correct amount of pressure applied would have interfered with securing tissue penetration of the preservative, the forming members should be applied directly upon the affected area and maintained in place under pressures of as much as 25 to 50 pounds. These pressures should remain constant for from 1 to 2 hours.

In conjunction with the use of the forming members and according to the novel method disclosed herein, the flow of the embalming fluid may also be controlled by dilation and constriction of the vascular system within the particular part or area which is being treated. For example, in the temple area T, if it is desirable to exclude the embalming fluid or at least to prevent excessive assimilation of fluid in that area, the area may be cooled so as to cause capillary constriction within the area and hence to inhibit free flow in this area while maintaining the surrounding areas at normal temperature so that there is a normal flow of embalming fluid therein. On the other hand, if it is desirable to build up the temple area because of undue emaciation, heat may be applied thereto cause capillary dilation which will encourage freer flow of the embalming solution to the warmed area. Both the heating and cooling are carried out in conjunction with the forming members by conducting the heat or cold through the forming members directly to the underlying tissue.

In certain instances this procedure for concentrating the embalming fluid in given areas is especially advantageous in that it may be employed to render a given portion or area more rigid than other parts, thereby to prevent sag-

ging of the body after it has been finally arranged in the desired position. For example, by applying heat to the neck the volumetric capacity of the vascular system therein may be increased so that a large quantity of fluid may be concentrated in the neck which upon setting will preclude any movement of the head once it has been suitably arranged.

The apparatus which is used for carrying out the foregoing method includes a number of rigid forming members preferably made of plasticized wood fiber or some synthetic resinous material which may be easily molded to the proper form and which will not be damaged by repeated usage. These members are made up in sets to be applied to the areas referred to above and are provided with forming surfaces which are the converse of the average contours of normal American faces.

As illustrated, the forming member for the thyroid area, one of which is shown at 12 in Fig. 5, is comprised of a generally rectangular piece of plastic, longitudinally concavo-convex (Fig. 6) so as to fit around one side of the neck, as illustrated in the dot and dash lines of Fig. 1, and has a high portion 14 at its rear end which is adapted to lie close under the skull bone at the back of the neck. The rear end is beveled at the inside and the forward end 16 is beveled at the outside so that the bordering ends diverge from the areas upon which they are placed thereby precluding any possible mark where the mold has been applied that will cause a blemish. The cheek forming members 18, shown in Figs. 7 and 8, are somewhat egg-shaped, having a broad end 20 which occupies the forward part of the cheek and a narrow end 22 which is situated in the crotch at the hinge of the jaw bones. The molding surface 18' is slightly convex so as to impart a slight concavity to the cheek. The temple forming members 24 are nearly elliptical in shape and are placed with their longitudinal axis nearly vertical. The members 24 also have a slightly convex molding surface 24'. The eye forming members 26 are generally almond shape and have a spheroidal cavity 28 therein which is the reverse of the contour of the cornea of the eye. The bordering part 29' is shaped to fit into the eye socket around the eye. The lower lip and chin forming member 29, shown in Figs. 13 and 14, is generally hoof-shaped, has a shallow recess 30 therein from which there projects nearly centrally thereof a transverse protuberance or ridge 32 which is a converse of the dimple or crease between the lip and the chin, and a bordering rim 34 shaped to overlie the surface of the lower lip. The upper lip forming member 36 (Figs. 15 and 16) is generally semi-circular, has a subjacent transverse web 38 arranged to conform to the under portion of the upper lip, and a protuberance 40 arranged to occupy the gutter extending from the nose down to the top of the upper lip.

With the foregoing parts available, a very simple use is illustrated in Fig. 2 wherein the right and left eye forming members 26 are applied over the eyes to hold them against excessive bulging and to insure proper location of the surrounding tissue. To hold the eye forming members in place there is provided a binding member 42 (Figs. 4 and 17) which, as shown in Fig. 4, is in the form of a narrow, hollow, flexible bag 42 made of rubber-like material, for example latex, the ends of which have grommets 44 therein in which may be tied cords 46. The binding member 42 is placed about the head, as shown in Fig. 2, so as to embrace the

eye forming members which are made substantially flat on their exposed sides and to pass around the sides of the head where their ends are secured in place by tying the ends of the cords

5 46 as at 52. If pressure alone is to be employed when treating the eyes with the eye forming member, the elasticity of the bag may be relied upon to afford the desired degree of pressure or may be filled with water or some other fluid at normal 10 temperature through a filling opening 48 in which there is a filling nipple provided with a closure 50. Introduction of the fluid to the binding member distends it and causes it to apply equal pressure uniformly to both of the eye forming members 15. In Fig. 3 there is illustrated the simultaneous use of all of the forming members, and it is apparent that this can conveniently be done by resting the head on a support S, applying the various forming members to their proper places 20 and binding them in place by using several of the binding members 42. As illustrated, one binding member 42 may be secured about the neck to hold the thyroid forming members 12 in place, another may be secured about the lips and chin to hold 25 the upper and lower lip forming members and also the cheek forming members in place, while a third may be used to hold the eye forming and temple forming members in place.

The use of the tubular or bag-like binding member affords, in addition to the pressure, a convenient and desirable way for either heating or cooling the forming members and thus to conduct heat or cold to the underlying tissue which in turn expands or contracts the vascular system in 30 the portion or area to which the members are applied. This provides a means for controlling the flow of the embalming fluid in the portion or area, for if the forming member is cooled to a subnormal temperature the underlying area will 35 be cooled, thereby causing capillary contraction and resistance to assimilation of the embalming fluid by this area; thus, when it is desirable to prevent swelling of the area, the forming member will be cooled. If, on the other hand, it is desirable 40 to build up an area which is seriously emaciated, the forming member may be heated so as to conduct heat to the underlying tissue to cause capillary expansion and thereby to permit assimilation of an excessive amount of embalming fluid, and hence to plump up that area. It has also been found that this control of the 45 flow of embalming fluid to a given portion or area is useful in making certain parts of the neck and face more rigid so as to resist sagging and displacement after the body has been satisfactorily oriented which might result in an unnatural appearance. For example, a concentration of the fluid may be produced in the back part of the neck and the jowls by warming to 50 expand the vascular system in these areas while maintaining the other areas to which the forming members are applied cool so that they resist excessive accumulation of the embalming fluid. This may be accomplished by placing the latex 55 water bag with hot water therein directly upon the neck so that the heat is transferred to the underlying tissue, thereby encouraging increased saturation of the tissue and greater final tissue fixation. By thus enabling the embalmer to 60 secure greater tissue fixation the value of body-positioning devices which are of unquestionable value in posing stout, short-necked bodies is not lost by lack of sufficient fixation. Hence, when 65 the body is removed from the positioning device 70 75

and placed in the casket it will not undergo subsequent changes.

In addition to affording means for molding the features of the cadaver and controlling the quantity of embalming fluid delivered to specified areas, the forming members afford means for teaching apprentices who are engaged in learning the business of embalming by giving them an accurate replica in converse of the average facial contour.

The molding members may also be employed together with moldable plastic materials when there are parts which must be built up because of traumatic injuries and are not susceptible of sufficient swelling according to the foregoing practice of injecting an excessive amount of embalming fluid into that area. For example (Fig. 18), a seriously emaciated cheek or a cheek which has been partially destroyed by disease or injury may be restored to its normal contour after the arterial injection by properly cauterizing the area, drying it, placing on the area or in the opening therein a moldable material *m* to fill it slightly above the desired contour, and applying the molding member to that part to cause the moldable material to take the natural contour. Since the edges of the molding members are curved outwardly away from the face, any excessive material may be squeezed out from under the molding members and readily removed, and any line of demarcation quickly eliminated by a molding tool. By firmly pressing the molding member upon the moldable material, the material itself is secured more firmly to the area than is possible if the customary method of lightly filling the depression is followed. Although plaster of Paris is not recommended as a filler in such cases, it too can be used and quickly and accurately molded by the same method as suggested in using pliable material.

The forming members may even be used to correct improperly embalmed cadavers by applying the forming members to the embalmed body, filling the binding members with hot water and allowing the pieces to be held in contact with the features which are to be corrected for several hours under pressures of 10 to 20 pounds. Sufficient softening will occur due to the application of heat to permit conformation of the areas being treated to the forming members.

In certain instances, bodies will have pouches formed under the eyes or upon the lips and neck. These pouchy areas offer less resistance to the entrance of the embalming solution and become partially enlarged causing wrinkles to appear. These wrinkles may be avoided if the proper forms are placed over the areas before arterial injection is begun and a light pressure of approximately $\frac{1}{2}$ pound is maintained during the injection period. This light pressure may be secured by placing a wet towel or absorbent cotton upon the forms.

It should be understood that the present disclosure is for the purpose of illustration only and that this invention includes all modifications and equivalents which fall within the scope of the appended claims.

We claim:

1. In the art of embalming a cadaver, the method of preventing excess assimilation of arterially injected embalming fluid by a specific portion only of the cadaver which comprises as steps, applying pressure by means of a rigid contouring mold to that portion only of the cadaver which is to be protected from excess assimilation of em-

balming fluid thereby to constrict the vascular system in that portion while leaving adjacent portions unconstricted, and maintaining the pressure during injection of the fluid and setting thereof.

2. In the art of embalming a cadaver, a method for preventing accumulation of a superfluous quantity of embalming fluid in specific portions of the body, which through disease, have an abnormally low resistance to permeation, said method comprising applying pressure locally, by means of a rigid part, having a contact surface which is the converse of the normal shape of said part, to the afflicted portion to restrict the flow of fluid through the vascular system in that portion while leaving the adjacent areas uncompressed so that the vascular system thereabout will have its normal capacity, and while maintaining said pressure injecting the embalming fluid and allowing it to set.

3. In the art of embalming a cadaver, a method for controlling the local assimilation of arterially injected embalming fluid by a selected portion of the cadaver, comprising modifying the volumetric capacity of the vascular system in said portion only by varying the temperature in said portion only while leaving the remainder of the body at normal temperature, and while maintaining said modified temperature condition in said selected portion injecting the embalming fluid and allowing it to set.

4. In the art of embalming a cadaver, a method for restoring an emaciated portion to its normal condition comprising applying pressure to the area surrounding the emaciated area, providing a contouring surface which is the converse of the normal condition of the part, injecting embalming fluid under pressure to cause an accumulation of fluid in the tissue of the emaciated part of sufficient quantity to plump the area and bring it into surface contact with the contouring surface, and maintaining the contouring member in place while the fluid sets.

5. A method for treating a cadaver during injection and setting of the embalming fluid comprising applying a rigid contouring member having an unchangeable surface contour, to a selected area of the body, binding the contouring member in place to the body, injecting the body with the fluid, and leaving the contouring member in place until the fluid sets, and then removing the contouring member.

6. A method for preventing local distention in a particular part of a cadaver during injection of the embalming fluid comprising applying a rigid mold member, having an unchangeable surface contour, to said part prior to injection of the embalming fluid, binding the mold member to said part, injecting the body with fluid, and leaving the mold member in place until the fluid has set and then removing the mold member.

7. A method for reducing local distention that is present in a particular part of a cadaver prior to the embalming comprising applying a rigid mold member, having an unchangeable surface contour, to said distended part, binding the mold member in place under sufficient pressure to reduce the distended part to its normal contour, injecting the embalming fluid and leaving the mold member in place until the fluid sets, and thereafter removing the mold member.

8. A method for changing the contour of a portion of a cadaver comprising applying a rigid mold member having the desired contour to said

11

portion, binding the member in place, injecting the embalming fluid and leaving the member in place until the fluid sets, and thereafter removing said member.

9. A method for restoring a shrunken portion of a cadaver to a lifelike contour comprising applying a rigid contouring member having a surface contour of the desired shape, binding it in place over the shrunken part, injecting the embalming fluid in sufficient quantity to inflate said shrunken portion into contact with the rigid contouring member and leaving the part in place until the fluid sets, and thereafter removing said member.

10. A method for controlling the quantity of embalming fluid which will be taken up by a given area of a cadaver, comprising applying a member having a surface contour corresponding substantially to the part of the body in which control is to be had, binding the member in place under pressure, injecting the fluid and leaving the member in place until the fluid has set, whereupon the part may be removed.

11. In the art of embalming a cadaver, a method for controlling the assimilation of arterially injecting embalming fluid by a cadaver comprising dilating the vascular system in portions thereof where an accumulation of fluid is desired and contracting it in areas where a dearth of fluid is desired, injecting the embalming fluid under pressure, and maintaining the dilated and contracted areas while the fluid sets.

12. In the art of embalming a cadaver, a method for controlling the assimilation of arterially injected embalming fluid by a cadaver comprising constricting the vascular system in selected portions wherein a dearth of fluid is desired without disturbing the normal condition of the remainder of the body, injecting the embalming fluid under pressure, and maintaining the constricted area while the fluid sets.

13. In the art of embalming a cadaver, a method of controlling the assimilation of the arterially injected embalming fluid by a selected portion only of the body which comprises as steps, applying heat locally to said selected portion thereby to dilate the vascular system of said portion while keeping the remainder of the body at normal temperature and keeping said selected portion only at an elevated temperature while injecting the body as a whole with the fluid, whereby said selected portion receives more of the fluid than it would were it at the same temperature as the remainder of the body.

14. In the art of embalming a cadaver, a method of controlling the assimilation of the arterially injected embalming fluid by a selected portion only of the body which comprises as steps, applying cold locally to said selected portion thereby to contract the vascular system of said portion while maintaining the remainder of the body at normal temperature and keeping said selected portion only at sub-normal temperature while injecting the body as a whole with the fluid, whereby said selected portion receives less of the fluid than it would were it of the same temperature as the remainder of the body.

15. In the art of embalming a cadaver, a method of controlling the assimilation of the arterially injected embalming fluid comprising applying a pressure in the form of a molding member to that portion of the body from which an excess of fluid is to be excluded, conducting cold to the area under pressure to cause capillary constriction in the underlying tissue thereby further to exclude

12

the fluid, injecting fluid arterially under pressure and maintaining the pressure and cold while the fluid sets.

16. In the art of embalming a cadaver, a method of controlling the assimilation of the arterially injected embalming fluid comprising placing a forming member on the part of the body from which an excess of fluid is to be excluded, cooling said member to cause capillary constriction in the underlying tissue, and while maintaining the member in place and at a subnormal temperature injecting the embalming fluid and allowing it to set.

17. In the art of embalming a cadaver, a method of controlling the assimilation of the arterially injected embalming fluid comprising placing a forming member on the part of the body which is to be treated, heating the member to cause capillary expansion, and while maintaining the member in place and at an elevated temperature injecting the fluid into the body in sufficient quantity to cause the underlying tissue to expand into contact therewith and then allowing the fluid to set.

18. In the art of embalming a cadaver, a method of building up a sunken area comprising placing a forming member on the area the surface of which is the converse of the desired ultimate shape of the sunken area and has a bordering reversely curved surface which merges with the forming area nondefinitively, with the bordering area in firm contact with the body, conducting heat to the member to cause capillary expansion of the underlying tissue, and while holding the member in place and maintaining an elevated temperature, injecting the embalming fluid under pressure in sufficient quantity to cause the underlying tissue within the border of the forming member to swell into contact with the surface thereof and then allowing the embalming fluid to set.

19. A device for use in embalming comprising a rigid member applicable to a cadaver, said member having a surface contour the converse of which represents substantially the normal lifelike contour of said part, said surface area merging nondefinitively with a bordering surface of reverse curvature, an inflatable member adapted to be placed about the cadaver in the vicinity of the member to embrace and hold the member in place, and means releasably securing the ends of the inflatable member together.

20. A device for use in embalming comprising a rigid member applicable to a selected part only of the cadaver, wherein a different volume of fluid in the vascular system at that part is desired than would normally exist therein without disturbing the normal condition of the remainder of the body, said member having a surface contour the converse of which represents the normal lifelike contour of said part, said surface area merging nondefinitively with a bordering surface of reverse curvature, a band adapted to be placed about the cadaver in the vicinity of the member and to hold the member in place, said band having a cavity therein adapted to receive a heating medium, and means for releasably securing said band to the cadaver.

21. A device for use in embalming comprising a rigid member applicable to a cadaver, said member having a surface contour the converse of which represents substantially the normal lifelike contour of said part, said surface area merging nondefinitively with a bordering surface of reverse kind, a hollow band adapted to be placed

about the cadaver in the vicinity of the member and to hold the member in place, said band having a charging opening therein into which a fluid having a given heat content may be injected, and means for releasably securing said band to the cadaver.

22. Apparatus for use in embalming comprising a plurality of rigid forming members, each of said members having a surface contour the converse of which represents substantially the normal lifelike contour of a given part of the cadaver, a binding member adapted to be placed about the cadaver to hold said members in their respective places, said binding member having flexible walls and a charging opening through which a fluid may be introduced to the interior thereof to inflate the same and to conduct heat to the underlying forming members while held in contact with the cadaver.
